CLAIM

The ornamental design for a soft magnetic core piece for soft magnetic core assembly, as shown and described.

DESCRIPTION

FIG. 1 is a perspective view of a first embodiment of a soft magnetic core piece for soft magnetic core assembly showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view thereof, shown in environmental use;

FIG. 9 is a perspective view thereof, shown in an alternate environmental use;

FIG. 10 is a perspective view of a second embodiment of a soft magnetic core piece for soft magnetic core assembly showing our new design;

FIG. 11 is a front elevational view thereof;

FIG. 12 is a rear elevational view thereof;

FIG. 13 is a top plan view thereof;

FIG. 14 is a bottom plan view thereof;

FIG. 15 is a left side elevational view thereof;

FIG. 16 is a right side elevational view thereof;

FIG. 17 is a perspective view thereof, shown in environmental use; and,

FIG. 18 is a perspective view thereof, shown in an alternate environmental use.

The broken lines shown represent environmental structure and form no part of the claimed design.
